UNITED STATES PATENT OFFICE.

OSCAR HEYMAN, OF NEW YORK, N. Y.

BOTTLE-CAPPING MACHINE.

SPECIFICATION forming part of Letters Patent No. 703,203, dated June 24, 1902.

Application filed March 26, 1902. Serial No. 100,036. (No model.)

To all whom it may concern:

Be it known that I, OSCAR HEYMAN, a citizen of the United States, and a resident of New York, in the county of New York and 5 State of New York, have invented certain new and useful Improvements in Bottle-Capping Machines, of which the following is a specification.

My invention relates particularly to improvements in machines whereby caps or capsules are applied to the necks and heads of bottles, and its objects are, among others, to provide a simple and easily-operated mechanism of this character which will securely 15 apply the said caps or capsules and which may be used for applying the same to bottles of varying length and diameter of neck.

It consists of the combination and arrangement of parts hereinafter described and 20 claimed, and illustrated in the accompanying drawings, in which—

Figure 1 is a vertical cross-section of the elastic sleeve and cylinder within which the same is located, taken on the line 1 1 of Fig. 25 2. Fig. 2 is a vertical longitudinal section of a bottle-capping machine, showing my improvements. Fig. 3 is a like section of the sleeve, cylinder, and plunger, showing the use of a plunger of different length. Fig. 4 30 is a plan of the outer cylinder.

The cylinder A is adapted to receive the elastic sleeve B, which fits snugly therein, and also the sliding plug C, which has a conical depression C' at its rear end adapted to 35 receive the end D' of the plunger-rod D. At its rear edge the cylinder is provided internally with an annular boss A', which prevents the plug and sleeve from passing out therethrough. At its outer end the cylinder is

40 provided with a removable cap E, having a central opening E', of lesser diameter than the elastic sleeve B and adapted to hold the said sleeve in position and prevent it from leaving the cylinder when pressure is applied 45 at the rear end thereof. The edges E' of the cap, against which the sleeve abuts, are beveled, so that the tendency of the edges of the sleeve will be to wedge themselves into the corners thereof when the pressure is applied.

50 The cap E is removably secured to the cylinder by the lugs E', which are preferably four in number and pass through the openings

A³ in the annular rib A² of the cylinder leading to the groove A⁴ and hold the said cap by coming in contact with the rib. The rib 55 is provided with beveled portions a², adjacent to the openings therein, which will cause the cap to be pressed tightly against the end of the cylinder when the same is rotated and the lugs E³ caused to slide along the same. 60 The cap is also provided with a handle E⁴, by which it may be turned and which affords a suitable leverage for tightening the same. The cylinder is preferably made integral with the bed-plate F, which is provided at its opposite end with standards F', to which the lever G is pivotally secured by means of the bolt G'. A short distance from the pivot-bolt G' the rod H is secured to the lever by means of the bolt H', so that when the lever is drawn 70 forward the bolt, together with the sleeve I and the plunger-rod D at the other end of the sleeve, is thrust forward. The sleeve I is inferiorly threaded at its rear end to receive the threaded outer end of the bolt H, while 75 its other end is adapted to receive the rear end D² of the plunger D, which is of reduced diameter. A partition I' is provided at or near the center of the sleeve I, against which the rear end of the plunger D abuts. The 80 plungers D may be made of different lengths to accommodate different lengths of the rubber sleeves which are used, according to the length and size of the bottle-neck upon which the cap is to be placed. This is desirable, 85 owing to the fact that unless the head of the bottle is pressed against the sliding plug C while the cap is being applied the said cap will have a tendency to bulge or wrinkle at the top. 90

The operation of this device is as follows: The cap or capsule J is first placed loosely over the neck of the bottle and the said neck then introduced into the rubber sleeve B. The lever G is then drawn forward and downward, causing the plunger D to press against the sliding plug C and move it forward. This movement compresses the rubber sleeve B, causing it to expand inwardly and press the said capsule tightly around the head and 95 neck of the bottle. Longitudinal grooves B' are provided on the interior of the sleeve to admit of this inward expansion and also to take up the slack in the capsule when it is 100

pressed around the bottle-neck. This will leave a small rib or fold corresponding to the grooves on two sides of the cap, which may be flattened down by turning the bottle 5 partly around and applying the pressure again.

A limited adjustment of the plunger to vary the pressure upon the bottle-neck may be obtained by rotating the sleeve I, and thus 10 cause the plunger to approach or recede from the plug C, and by the use of this adjustment bottles having necks of varying diameter may be capped without necessitating the use of different-sized sleeves.

15 What I claim is—

1. In a device of the character described, the combination of a cylinder, an elastic sleeve fitted therein, a removable cap on the end of said cylinder, a central opening in 20 said cap of lesser diameter than the bore of the cylinder, a portion of said cap, extending from the said opening to the inner surface of the cylinder, inwardly beveled, and means for causing the said sleeve to be pressed 25 against the said beveled portion.

2. In a device of the character described, the combination of a cylinder, an elastic sleeve therein, a removable cap, a central opening in the said cap, a sliding plug within 30 the said cylinder, a plunger having one end in contact with the said plug, a sleeve into which the opposite end of said plunger passes,

an interior threaded portion of said sleeve at its opposite end, and a rod threaded therein and means for causing the said rod to recipro- 35 cate.

3. In a device of the character described, the combination of a cylinder, an elastic sleeve fitted therein, a cap on the end of said cylinder, a central opening in said cap of 40 lesser diameter than the bore of the cylinder, and an inwardly-beveled portion of said cap extending from the central opening to the inner surfaces of the cylinder, and means for causing pressure upon the end of the 45 said sleeve opposite the cap.

4. In a device of the character described, the combination of a cylinder, an elastic sleeve therein, a cap on the end of said cylinder, a central opening in said cap, a sliding plug within said cylinder, a plunger having one end in contact with said plug, a sleeve which receives the outer end of said plunger and a rod adjustably connected to the end of said sleeve opposite the one which 50 receives the end of the plunger.

Witness my hand this 18th day of March, 1902, at the city of New York, county and State of New York.

OSCAR HEYMAN.
